United States Patent Office

Des. 188,854
Patented Sept. 20, 1960

188,854

ROUNDABOUT

Carl L. Hannas, St. Paul, Alberta, Canada

Filed May 8, 1959, Ser. No. 55,849

Term of patent 3½ years

(Cl. D34—5)

FIG. I

FIG. 2

Fig. 1 is a perspective view of a roundabout showing my new design; and

Fig. 2 is a side elevational view thereof, the opposite side being substantially a mirror image thereof.

I claim:

The ornamental design for a roundabout as shown and described.
